UNITED STATES PATENT OFFICE.

ALPHAEUS C. BAIMBRIDGE, OF ORCUTT, CALIFORNIA.

PLUNGER-PUMP.

1,188,605.

Specification of Letters Patent. Patented June 27, 1916.

Application filed March 9, 1915. Serial No. 13,213.

To all whom it may concern:

Be it known that I, ALPHAEUS C. BAIMBRIDGE, a citizen of the United States, residing at Orcutt, in the county of Santa Barbara and State of California, have invented new and useful Improvements in Plunger-Pumps, of which the following is a specification.

This invention relates to plunger-pumps 10 designed for use in deep wells, but is applicable to any form of plunger-pump.

The object of this invention is to provide a pump in which the flow of liquid between the plunger and the barrel will be prevented 15 in a simple and effective manner.

In deep well-pumps, such as oil-wells, in which sand is mixed with the fluid to be pumped, great loss of time, labor and expense results from the wearing away of 20 parts of the pump, by sand which is carried by the fluid into the space between the plunger and the working barrel, and which necessitates the pulling of the pump and the replacement of worn parts.

The principal object of this invention is 25 to avoid the difficulties above referred to by novel and improved means, whereby a fluid tight seal between the plunger and the working barrel is automatically maintained, notwithstanding the continuous wear of the parts.

It will be understood that this invention is not limited to the specific construction described, but may be embodied in other forms 35 within the scope of the appended claims.

Figure 1 is a vertical sectional elevation of a pump in place inside a well casing and constructed in accordance with this invention. Fig. 2 is an enlarged, sectional view 40 of the plunger and the bushing expansion member. Fig. 3 is a fragmentary view of the bushing showing the expansion member in position. Fig. 4 is a cross-section on line 1—1, Fig. 1.

1 represents the well-casing in which the working barrel 2 is located. A standing valve is positioned in the lower end of the working barrel, said valve comprising the tubular valve-body 3 provided at its upper 50 end with a screw threaded neck 4 to receive and engage the valve cage 5 holding the valve 6 in position. An internal shoulder 7 of said body holds a valve seat 8, on which the valve 6 is seated. The lower end of the 55 valve-body 3 is tapered and adapted to be seated on an inwardly tapered annular ring

9, screwed into the lower end of the working barrel 2. From the top of standing valve cage 5 a rod 10 extends upwardly into a plunger 11, and is provided at its upper end with a head 12, said rod being provided at its lower end with a threaded neck 13, which is screwed into a corresponding aperture in the valve cage 5. The cylindrical, rigid plunger body 11, is of less diameter than the working barrel 2, and is provided at its lower end with an externally threaded neck portion 13, on which a plunger head 14 is screwed. Said head 14 comprises a collar 15 screwed on to the plunger neck 13. Centrally located in the head 14 is a circular aperture 16 through which the rod 10 extends, and through which the liquid to be pumped enters the plunger. In order to prevent the head 14 from jarring loose and becoming unscrewed, a locking pin 16' is provided, securely holding the head 14 in place on the plunger. On top of head 14, a circular nut 17 is screwed on the threaded neck 13 of the plunger, said nut providing a seat for the expansible cup-shaped plunger bushing 18. Bushing 18 consists of a cup-shaped body, preferably made of steel, and of a size to fit snugly in the working barrel 2. An annular space 18' is formed between 70 the bushing and the plunger. The bottom of said bushing 18 has an aperture 19, of the same diameter as the external diameter of the plunger 11. Nut 20 screwed on plunger neck 13, above the bushing bottom holds 75 the bushing securely in position. Nuts 17 and 20 form a fluid tight seal between the plunger and bushing. Above the bushing 18 is a tubular mandrel 22 for expanding the upper rim of the bushing 18. Said 80 mandrel 22 is loosely mounted on the plunger 11. Its lower portion is of a frusto-conical shape, and adapted to extend for a short distance into the annular space 18', and to force the upper rim 21 of the bushing 85 against the wall of the working barrel 2, forming a close fitting joint or seal, as will be hereinafter explained. Said mandrel, like the bushing 18, is constructed of steel, but it is obvious that any other suitable metal may be substituted for either or both of said elements.

In order to reduce the friction between the expansion mandrel, a plurality of annular channels 23 are provided on mandrel 22. 95 Such channels, however, may be omitted in constructing the mandrel. The upper part 100

of the plunger 11 is slightly enlarged, forming an annular shoulder 24 located a short distance above the mandrel. The object of said shoulder is to limit the upward movement of the expansion mandrel 22. The upper end of plunger is externally threaded, and the valve cage 25 is screwed thereon. On the internal shoulder 26 at the upper end of the plunger 11, a valve seat 27 is positioned seating valve 28 of any preferred construction. The upper end of valve-cage 25 is provided with an externally threaded neck 29 to which the sucker rod 30 is secured.

15 The assembling of the various parts and the operation of the pump will be easily understood from the foregoing description. The mandrel 22 is slipped on to the plunger from the lower reduced end until it meets 20 the shoulder 24, then nut 20 is screwed into place on the lower neck of the plunger; next the cup-shaped bushing 18 is positioned, the bottom 19' being securely held against nut 20 by nut 17. Rod 10 is inserted and then 25 collar 14 is screwed into place, and securely locked by pin 16'.

Operation: When plunger 11 is reciprocated, standing valve 6 opens on the upward stroke, and the fluid enters through aperture 30 16 into the plunger barrel, filling the same, the upper valve 28 remaining seated. On the downward stroke, standing valve 6 closes and upper valve 28 opens. On further operation of the pump the fluid will be lifted to 35 the surface, as will be understood. Owing to the sand present in the fluid to be pumped, there is considerable wear between the working barrel and the plunger, with the result that in a short time the parts of the plunger 40 which contact with the wall of the working barrel fit loosely, and a considerable portion of the fluid will leak from the column supported by the upper valve 28, down below said upper valve, thus greatly impairing 45 the efficiency of the pump. As the leakage increases, it necessitates the pulling of the pump, and replacing the worn parts. The present invention avoids this objection in providing automatic means for effecting 50 a fluid tight joint or seal, between the wall of the working barrel and the plunger, thus prolonging the life of the pump indefinitely.

As the rim 21 of the bushing becomes worn, the expansion mandrel 22 will force the 55 worn rim outwardly in close contact with the wall of the working barrel. The mandrel is of sufficient weight to gradually and successively expand and force the rim 21 against the wall of the working barrel. The 60 weight of the column of fluid above the plunger assists the mandrel in expanding the bushing 18 as it becomes worn.

The operation of the mandrel is clearly 65 shown in Fig. 3. Shoulder 24 will prevent the mandrel from sticking against the wall

of the barrel. In the normal operation the mandrel will remain seated with its lower edge within the annular space 18' against the inner upper edge of the bushing. But it will function satisfactory also when it 70 reciprocates with the limited movement allowed by the bushing and the shoulder 24. When it is desired to pull the pump the lost motion connection rod 10 between the plunger barrel and standing valve will pull 75 the latter, the head 12 contacting with the plunger 11, as will be understood.

I claim:

1. A plunger-pump comprising a working barrel, a plunger inside said barrel, a standing valve below said plunger, a lost motion connection between said standing valve and said plunger, a valve mounted at the upper end of the plunger, means for reciprocating said plunger, a metal cup-shaped bushing between said plunger and said barrel, the lower end of said bushing being secured to the plunger and forming a fluid-tight seal therewith, the upper part of said bushing forming an annular cup-shaped space with said plunger, a tubular expansion mandrel slidably mounted on said plunger, said mandrel being of frusto-conical shape at its lower end, and adapted to extend for a short distance into said cup-shaped annular space, a shoulder on said plunger above the mandrel limiting the upward movement of said mandrel, whereby a fluid-tight seal between said plunger and said barrel is automatically maintained during the operation of the pump. 90

2. A plunger-pump comprising a working barrel, a plunger inside said barrel, a standing valve below said plunger, a valve mounted at the upper end of said plunger, 105 means for reciprocating said plunger, a metal bushing between said plunger and said barrel, the lower end of said bushing being secured to the plunger and forming a fluid-tight seal therewith, a tubular expansion 110 mandrel slidably mounted on said plunger, said mandrel being of frusto-conical shape at its lower end and adapted to expand the upper part of said bushing, whereby a fluid-tight seal between said plunger and said 115 barrel is automatically maintained during the operation of the pump.

3. A plunger-pump comprising a working barrel, a plunger inside said barrel, a standing valve below said plunger, a valve 120 mounted at the upper end of said plunger, means for reciprocating said plunger, a metal bushing between said plunger and said barrel, one end of said bushing being secured to said plunger and forming a fluid-tight seal therewith, a tubular mandrel 125 loosely mounted on the plunger adapted to expand the other end of the bushing against the wall of said barrel whereby a fluid-tight seal between said plunger and said barrel 130

is automatically maintained during the operation of the pump.

4. A plunger-pump comprising a working barrel, a plunger inside said barrel, a standing valve below said plunger, a valve mounted at the upper end of said plunger, means for reciprocating said plunger, a metal bushing between said plunger and said barrel, one end of said bushing being secured to said plunger and forming a fluid-tight seal therewith, an expansion member loosely mounted on said plunger adapted to expand

the other end of said bushing against the wall of the said barrel, whereby a fluid-tight seal between said plunger and said barrel is 15 automatically maintained during the operation of the pump.

In witness that I claim the foregoing I have hereunto subscribed my name this 27th day of February, 1915.

ALPHAEUS C. BAIMBRIDGE.
